Primary Examiner — David Muller(74) *Attorney, Agent, or Firm* — QuickPatents; Kevin Prince(57) **CLAIM**

I claim the ornamental design for a disposable syringe with unit markings for the dosage and administration of refined forms of botulinum toxin A, as shown and described.

DESCRIPTION

FIG. 1 is a perspective view of a disposable syringe with unit markings for the dosage and administration of refined forms of botulinum toxin A, showing my new design;

FIG. 2 is a top plan view thereof;

FIG. 3 is a bottom plan view thereof;

FIG. 4 is a left-side elevational view thereof, the right-side elevational view being a mirror image thereof;

FIG. 5 is a front elevational view thereof; and,

FIG. 6 is a rear elevational view thereof.

The broken lines showing a logo in FIGS. 1 and 2 depict environmental matter and form no part of the claimed design.
